UNITED STATES PATENT OFFICE.

HARRY WEARNE, OF RIXHEIM, GERMANY.

DESIGN FOR A BORDER FOR WALL-PAPER.

SPECIFICATION forming part of Design No. 31,989, dated December 12, 1899.

Application filed November 14, 1899. Serial No. 736,998. Term of patent 7 years.

To all whom it may concern:

Be it known that I, HARRY WEARNE, a subject of the Queen of Great Britain, and a resident of Rixheim, Alsace, Germany, have invented and produced a new and original Design for a Border for Wall-Paper, of which the following is a specification, reference being had to the accompanying drawing, forming a part thereof, in which is represented a plan view of a section of border embodying the features of my design.

The leading feature of the design consists of a floral chain made up of a representation of roses, their buds, stems, and leaves arranged alternately with flowers of the daisy type and their buds, stems, and leaves.

In detail the design consists in the above-mentioned floral chain being located between parallel panels, which panels have connected diamond ornamentations and bead-like marginal portions.

Having thus described my invention, I claim as new and desire to secure by Letters Patent—

The design for a border for wall-paper as herein shown and described.

HARRY WEARNE.
